United States Patent Office

MATHIAS REDLINGER, OF FREEPORT, ILLINOIS.

Letters Patent No. 66,253, dated July 2, 1867.

IMPROVEMENT IN CORN-PLough.

The Schedule referred to in these Letters Patent and making part of the same.

TO ALL WHOM IT MAY CONCERN:

Be it known that I, MATHIAS REDLINGER, of Freeport, in the county of Stephenson, in the State of Illinois, have invented a new and useful Improvement on a Corn-Plough; and I do hereby declare that the following is a full, clear, and exact description of the construction and operation of the same, reference being had to the annexed drawing, making a part of this specification.

The nature of my invention is a lever, A, for raising and lowering and for adjusting the ploughs B to a proper depth in hard or soft and mellow ground, and also for the purpose of supporting the ploughs when not in use, and arranged with a movable bar or treadle, C, for the purpose of moving and adjusting the front ploughs to the rows of corn, and to avoid obstructions.

To enable others skilled in the art to make and use my invention, I will proceed to describe it as follows:

Figure 1 represents a top view,

Figure 2 a sectional elevation of the corn-plough.

A is the lever attached to a roller, E, for the purpose of raising or lowering the rear ends of the beams G by means of the connecting jointed rods H, to raise or lower the ploughs B. J is a semicircular rim with cogs or notches for retaining and holding the lever A in its proper place. K K are guides to steady, retain, and support the plough beams G. The movable bar C is operated by the driver's feet. It has a centre lever, L, connected to adjustable arms M, by which the ploughs are moved to either side.

What I claim as my invention, and desire to secure by Letters Patent, is—

The arrangement of the lever A with its roller E connected to beams G, and the treadle C as arranged with the ploughs B, when combined with the beams G, as herein described and for the purposes set forth.

MATHIAS REDLINGER.
